UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

SHOE-REMOVING MECHANISM

Application filed January 31, 1928, Serial No. 250,885. Renewed August 15, 1929.

This invention relates to machines for operating on shoes, and more particularly to means for removing shoes from the location or vicinity in which an operation is performed thereon or from the machine. The invention is herein illustrated in its application to a tennis shoe lasting machine of the type disclosed in Letters Patent No. 1,775,225, granted on September 9, 1930, upon my co-pending application Serial No. 58,944 filed on September 26, 1925. It is to be understood, however, that the invention is not limited in its applicability to machines of that particular type nor to lasting machines of any kind, but is generally applicable to machines of various kinds used in shoe manufacture. It should be further understood that the term "shoe" is herein used, unless the context requires a different interpretation, in a general sense to include a last with one or more parts of a complete shoe thereon, without reference to any particular stage in the manufacture of the shoe.

In the operation of some machines, such, for example, as the tennis shoe lasting machine shown in the above-mentioned Letters Patent, it is desirable that the operator be relieved of the necessity of removing the shoe after it has been operated upon, so that he may be free to prepare another shoe for presentation to the machine while operations on the preceding shoe are being completed and may be enabled to present the next shoe to the machine immediately upon the removal of the preceding shoe. The present invention provides improved means for thus removing the shoe, the construction shown comprising a simple yet effective organization including a shoe carrier having shoe-gripping means thereon and mounted for swinging movement to carry a shoe from the position in which it grips the shoe to the position in which it releases or discharges it. More particularly, in the illustrated construction the shoe carrier is thus movable about an axis extending lengthwise of the shoe through an arc of approximately 180° lifting the shoe from a support on which it is positioned bottom upward and automatically releasing it in a position in which it is bottom downward.

Aside from advantages due to simplicity in the mechanism thus provided, it is also an advantage to release the shoe bottom downward, since if deposited on a properly arranged chute or other support it will tend to maintain that position instead of tumbling about with possible danger of damage to its surface. Furthermore, it is contemplated that in some factories it may be desirable to carry the shoes from one machine or operating station to another on a belt conveyor, in which case it contributes to an orderly transfer of the shoes if they are received on the conveyor in upright positions.

The invention further provides novel means for insuring against damage to a machine through accidental interference between the shoe-removing mechanism and the means for operating on the shoe. The machine herein shown comprises heel-lasting mechanism which is moved into position to operate on the shoe by a spring controlled by the operator and is moved automatically away from the shoe after operating thereon, and shoe-removing mechanism which operates in an automatically determined cycle to grip the shoe by its heel end and lift it from its support and then to carry it to a different location and release it; and for the purposes in view there is provided a safety device controlled by the heel-lasting mechanism for preventing the operation of the shoe-removing mechanism unless the lasting mechanism has moved away from the shoe and for stopping the operation of the shoe-removing mechanism if the lasting mechanism is accidentally returned toward the shoe. Preferably, as shown, the safety device is limited in its effectiveness to a portion only of the cycle of operations of the shoe-removing mechanism, so that the lasting mechanism may be returned at the will of the operator into position to operate on another shoe presented on the shoe support before the shoe-removing mechanism has completed its cycle of operations without interfering with the completion of that cycle.

The above and other features of the invention, including various novel details of construction and combinations of parts, will now

be more particularly described by reference to the accompanying drawings and pointed out in the claims.

In the drawings,

5 Fig. 1 is a view in end elevation, with parts broken away, showing portions of a machine of the type illustrated in the above-mentioned Letters Patent with mechanism embodying the present invention applied thereto;

10 Fig. 2 is a plan view of a portion of the structure shown in Fig. 1;

Fig. 3 is a view in rear elevation of a portion of the structure shown in Fig. 1, with parts broken away;

15 Fig. 4 is a view in end elevation, with parts broken away, showing more in detail portions of the mechanism for gripping the shoe; and

20 Fig. 5 is a view in front elevation, with parts broken away, showing more in detail portions of the heel-lasting mechanism which is utilized for controlling, in part, the operation of the shoe-removing means.

The lasting machine to which the invention is herein shown as applied is fully illustrated and described in the above-mentioned Letters Patent, and accordingly only such parts of the machine as it is necessary to refer to for an understanding of the invention will be mentioned herein. The shoe 30 to be lasted, comprising a last with an upper and an insole thereon, is mounted bottom upward upon a shoe support 10. In this position the shoe is operated upon by toe-lasting mechanism 12, side-lasting mechanisms 14, 35 and heel-lasting mechanism comprising a heel band 16 and heel wipers 18. The machine is a power-operated machine and includes a vertically movable slide 20 (Fig. 1) associated with the toe-lasting mechanism 40 and another vertically movable slide 22 (Fig. 5) associated with the heel-lasting mechanism, as fully described in the earlier Letters Patent. In the cycle of operations of the machine both these slides are moved downwardly, and at the end of the cycle they are returned to their uppermost positions. The slide 22 has pivoted thereon at 24 an arm 26, a portion only of which is shown, provided with a roll 28 which is acted upon by a stationary cam plate 30 in the downward movement of the slide to swing the arm into the position in which it is shown in Fig. 5. In the return of the parts to starting positions the roll is released by the cam plate, permitting the arm 26 to swing toward the right (Fig. 5).

The heel band 16 and the wipers 18 are carried by an arm 32 which is fast on a rock-shaft 34 mounted to turn in bearings in a slide 36 which carries the shoe support 10. Initially the heel band and the wipers are held in the idle positions illustrated in Fig. 2 by means of a pivoted spring-controlled latch 38 (Fig. 5) on the slide 36 in engagement with a downward extension 40 of the arm 32.

When the latch 38 is swung downwardly to release the extension 40, the arm 32 is swung toward the shoe by a spring 42 to apply the heel band about the end of the shoe, as illustrated in Figure 5. The latch 38 is thus moved downwardly by the operator, prior to the starting of the power operation of the machine, through a manually controlled rod 44. After the operation of the lasting means upon the shoe the arm 32 and the heel-lasting devices supported thereon are returned into position to be held by the latch 38 by the upward movement of the slide 22 and the arm 26. For this purpose the arm 26 carries a pivoted finger 46 with a roll on its upper end arranged to engage one end of an arm 48 connected by gearing 50 to the arm 32. In the upward movement of the arm 26 the finger 46 thus acts on the arm 48 to swing the heel-lasting mechanism away from the shoe until it is caught by the latch 38, and as the arm 26 swings to the right (Fig. 5) about its pivot 24, the finger 46 is carried out from under the arm 48, so that in the operation of the machine upon the next shoe the arm 32 will be free to swing toward the shoe when it is released by the manually operated latch 38.

For removing the shoe from the machine after the different lasting mechanisms referred to have operated thereon and have moved away from the shoe, the invention provides a shoe carrier comprising an arm 52 which is mounted on a stud 54 on the frame of the machine for swinging movement about a horizontal axis extending in transverse relation to the height of the shoe, and in the construction illustrated lengthwise of the shoe. This arm has mounted thereon mechanism similar in construction to that shown in the previously mentioned Letters Patent for gripping or clamping the shoe on the shoe support 10 when the arm is moved toward the shoe and for releasing the shoe after the latter has been carried by the arm away from the shoe support. The shoe-clamping mechanism is shown in detail in Fig. 4 and for a better understanding of the invention will be herein described. It comprises a rod 56 and a hollow plunger 58 which are mounted for sliding movements upwardly and downwardly in a casing 60 carried by the arm 52 and have fast thereon at their lower ends a cross-bar 62 upon which is mounted a plate 64 for engaging the bottom face of the heel end of the shoe, this plate being mounted for tipping movements about a stud 66 on the cross-bar to permit it to adjust itself to the shoe. A spring 68 in the plunger 58 tends to move the plunger and the rod 56 downwardly in the casing 60 as far as permitted by a nut 70 on the upper end of the rod, and in operation permits the arm 52 and the casing 60 to continue their downward movement toward the shoe after the plate 64 has engaged

the shoe. Pivottally mounted on studs 72 on the opposite ends of the cross-bar 62 are shoe-gripping arms each comprising two members 74 and 76 which are movable together about the corresponding pivot stud 72 and may also move relatively to each other about the stud to a limited extent. Between each member 74 and the adjacent member 76 is a spring 78 which tends to swing these members apart, such relative swinging movement being limited by interengagement of shoulders 80 on the different members. Each of the members 76 carries at its lower end a shoe-gripping or clamping plate 82 which is preferably faced with some soft material, such as leather, and is mounted for limited turning movement about a stud 84 on a member 86 which is mounted likewise for limited turning movement about a stud 88 on the member 76 at right angles to the stud 84. A substantially universal connection is thus provided between the plate 82 and the member 76 to permit the plate to adjust itself to the shape of the shoe.

Each of the members 74 is provided with a roll 90 for engagement with a wedge face 92 on the casing 60, and a spring 94 connected to the opposite members 74 tends to swing these members toward each other and thus to hold the shoe-clamping plates 82 in a widely separated relation when permitted by the wedge faces 92. It will be understood that in the continued downward swinging movement of the arm 52 after the plate 64 has engaged the shoe, the wedge faces 92 act to swing the shoe-gripping arms 74, 76 about the studs 72 and thus to carry the clamping plates 82 into engagement with the opposite sides of the shoe, the springs 78 thereafter being compressed to some extent by movement of the members 74 relatively to the members 76 so that the shoe is clamped or gripped yieldingly on its opposite sides. The force with which the shoe is thus gripped can be varied by means of screws 96 which adjust the compression of the springs 78. At the end of the downward movement of the arm 52 the plunger 58 is locked against return movement relatively to the casing 60, so that when the arm 52 is swung upwardly the parts of the shoe-gripping mechanism will remain in operative engagement with the shoe and the shoe will thus be carried upwardly with them. For this purpose there is mounted on the casing 60 a latch 98 which is arranged to enter a notch 100 formed in the side of the plunger 58. This latch is controlled by a spring 102 which forces it into the notch 100 as soon as the latch has been carried downwardly far enough to enter the notch.

By reference to Fig. 1, it will be seen that in moving from the position in which it grips or seizes the shoe to the position (illustrated in dotted lines) in which it releases the shoe

the arm 52 with its shoe-gripping mechanism swings through an arc of approximately 180°, so that when the shoe is released it is positioned bottom downward. Partially enclosing the path of movement of the shoe-carrying means is a casing 104. At the end of the swinging movement of the arm 52 and the shoe-gripping mechanism the shoe is released by engagement of a roll 106, mounted on a stationary stud 108 on the casing 104, with the end portion of an arm 110 which projects outwardly through the casing 60 from the latch 98, whereby the latch is withdrawn from the notch 100 in the plunger 58 and the plunger is released to the action of the spring 68. To vary the time of the release of the shoe the stud 108 is adjustably mounted in a slot 110 in the casing 104.

The shoe when thus released may be received by any suitable means, the construction shown comprising a chute 112 which is inclined to such a degree that the shoe will slide down it readily, and at the end of the chute any suitable means (not shown) may be provided to receive the shoe. It will be understood that, since the shoe is engaged at its heel end only by the clamping plate 64, as soon as the plates 82 open to release the shoe the latter will by force of gravity tip downwardly upon the chute 112, the arrangement being such that the shoe will not turn over but will rest bottom downward on the chute. It is contemplated that in some factories it may be desirable to provide a conveyor, for example of the belt type, to carry the shoes from the chute 112 to the location where the next operation is to be performed thereon, and such a conveyor may be readily arranged to receive the shoes at the end of the chute while they are still positioned bottom downward.

For imparting to the arm 52 its operative movements, there is mounted on the stud 54 a gear wheel 114 which is secured to the arm 52 and is connected by an idle pinion 116 to a pinion 118 fast on one end of a shaft 120 which has fast on its other end a pinion 122 (Fig. 3) engaged by a vertically movable rack bar 124. The rack bar 124 is operated by a gear wheel 126 integral with which is a pinion 128 engaged and operated by a gear sector 130 on the upper end of an arm 132 which is mounted at its lower end on a rock-shaft 134. The arm 132 is provided with a roll 136 which lies in a cam groove 138 formed in one side of a cam wheel 140 fast on a shaft 142. It will be understood that the cycle of operative movements of the shoe-carrying arm 52 corresponds to a single revolution of the shaft 142 and the cam wheel 140.

For imparting operative movement to the shaft 142 there is provided at right angles thereto a shaft 144 which is operated by means hereinafter described and carries a worm 146 in operative engagement with a gear wheel 148.

148 on the shaft 142. The gear wheel 148 is not fast on the shaft 142, but is arranged to be connected thereto by a suitable clutch which is not shown in detail but may be a pin clutch of the same construction as a clutch illustrated in a similar relation in the Letters Patent hereinbefore mentioned. For controlling this clutch there is provided an arm 150 having on one side thereof a wedge face for disconnecting the gear wheel 148 from the shaft 142 in the manner characteristic of clutches of this type. The arm 150 is mounted on a rock-shaft 154 for upward swinging movement to start the shaft 142 in operation. The arm 150 is thus moved into position to start the operation of the shoe-removing means in automatically determined time relation to the operation of the lasting mechanism on a shoe. For this purpose there is also fast on the rock-shaft 154 an arm 156 connected by a link 158 to an arm 160 connected to which is another arm 162 arranged to be engaged at its outer end by a pawl 164 pivotally mounted on the end of a lever 166. The pawl 164 is controlled by a spring plunger 168 which swings it outwardly into position over the end of the arm 162 when permitted by the movement of the lever 166. The lever 166 is controlled by the vertically movable slide 20 hereinbefore referred to, which is provided with a pin 170 in position for engagement with one end of the lever 166 on the lower face of the lever. When the slide 20 receives its downward movement at the beginning of the power operation of the machine, the lever 166 is swung by a spring 172 into position to permit the pawl 164 to be swung outwardly over the end of the arm 162 by the plunger 168. When the slide 20 receives its upward movement in the return of the lasting mechanisms to idle positions after their operation upon a shoe, the pin 170 lifts one end of the lever 166 and thereby causes the pawl 164 to act through the connections described to lift the wedge arm 150 and thereby cause the gear wheel 148 to be clutched to the shaft 142 for operating the shoe-removing means. In this movement of the lever 166 the pawl 164 is finally carried downward past the end of the arm 162, so that the wedge arm 150 is permitted to swing back again, under the influence of a spring 174, into position to disconnect the shaft 142 from the gear wheel 148 at the end of a single revolution of the shaft.

55 The machine herein shown is also provided with means of substantially the same construction as shown in the previously mentioned Letters Patent for rendering the shoe-removing mechanism inoperative if desired. 60 This means comprises a hand lever 176 which is pivoted on the frame of the machine with its inner end in position to act on a pin 178 on the lever 166. A spring member 180 co-operating with a pin 182 on the lever 176 is 65 arranged to hold the lever either in the idle

position in which it is shown in Fig. 1 or in a position in which it engages the pin 178 and thus prevents the lever 166 from swinging in response to the downward movement of the slide 20.

70

The machine is further provided, for purposes of this invention, with means for insuring against such interference between the shoe-removing mechanism and the heel-lasting mechanism as might result in damage to the machine, in case, for example, the latch 38 should fail to hold the arm 32 when the latter is swung away from the shoe or in case the operator should accidentally release the arm 32 by movement of the latch-controlling rod 44 before the lasted shoe is lifted from the shoe support 10. The construction shown comprises automatic means for controlling the operation of the shoe-removing mechanism by the arm 32 in such manner as to bring that mechanism immediately to a stop if the arm 32 is returned toward the shoe prior to the lifting of the shoe from its support. For the purpose in view the shaft 144 is arranged to be driven through a sprocket wheel 184 which is not fast on the shaft, but may be connected therewith through a clutch, this sprocket wheel being driven by a chain 186 from a continuously running shaft 188. The clutch for connecting the sprocket wheel 184 to the shaft 144 is not shown in detail, but may conveniently comprise a pin clutch of well-known type controlled by a wedge arm 190 fast on a rock-shaft 192. A torsion spring 194 tends to swing the arm 190 into position to disconnect the sprocket wheel 184 from the shaft 144, and with the arm in that position the shoe-removing mechanism will be rendered inoperative even though the gear wheel 148 is connected to the shaft 142 by its clutch. The wedge arm 190 is arranged to be controlled by the arm 32 of the heel-lasting mechanism, and for this purpose the rock-shaft 192 carries an arm 196 connected by a link 198 to an arm 200 on a rock-shaft 202 provided with another arm 204 which carries a roll 206 arranged to be engaged by a lug 208 carried by the arm 32. It will be understood that when the arm 32 of the heel-lasting mechanism is swung outwardly away from the shoe, the lug 208 acts on the roll 206 to impart movement in the direction of the arrow to the link 198 and thereby to swing the wedge arm 190 into position to cause the sprocket wheel 184 to be clutched to the shaft 144, as illustrated in Fig. 3, so that movement is imparted to the shoe-removing means when the other clutch-controlling arm 150 is lifted in the manner hereinbefore explained. If, however, the arm 32 is not held by the latch 38 or is accidentally released so that it swings back again toward the shoe, the connections described permit the spring 194 immediately to swing the arm 190 into position to disconnect the sprocket wheel 184 from the shaft 144.

75 80 85 90 95 100 105 110 115 120 125 130

144 and thereby stop the operation of the shoe-removing mechanism. It will be evident that the sprocket wheel 184 and its clutch are rotated much more rapidly than the gear wheel 148, and accordingly the arm 190 will act on the clutch to stop the movement of the shoe-removing mechanism almost instantaneously in response to the return movement of the arm 32.

10 It will be understood that danger of breakage such as above referred to is confined to the earlier portion of the cycle of operations of the shoe-removing mechanism, since after this mechanism has moved into shoe-gripping 15 position and has lifted the shoe from the shoe support it is thereafter out of the way of the heel-lasting mechanism if the latter should return to operative position. It is, moreover, one of the objects in providing the automatic 20 shoe-removing mechanism that the operator shall be enabled to mount another shoe on the shoe support and to begin the operations thereon immediately after the preceding shoe has been removed from the support. The 25 machine is, therefore, further provided with means for rendering the arm 32 of the heel-lasting mechanism ineffective to stop the operation of the shoe-removing mechanism as soon as a shoe has been lifted from the shoe 30 support, so that the operator, after placing another shoe on the support, may release the arm by operation of the rod 44 in beginning operations on that shoe without preventing the shoe-removing mechanism from completing 35 its cycle of operations already begun. For this purpose the rock-shaft 192 has fast thereon an arm 210 connected by a link 212 to a lever 214 which is pivotally mounted at 216 and carries a roll 218 arranged to be engaged 40 by a side face of the cam wheel 140 to hold the wedge arm 190 in its inoperative position after the cam wheel 140 has turned through a predetermined portion of its cycle. The cam wheel 140 is provided on its side face 45 with a recess 220 in position to receive the roll 218 at any time during the early portion of the cycle of operations of the shoe-removing mechanism so as not to interfere with the function of the safety mechanism controlled 50 by the arm 32 in insuring against damage to the machine in the manner hereinabove explained. It will be understood that the recess 220 extends about the axis of the cam wheel 140 for a distance corresponding to 55 that portion of the cycle of operations of the shoe-removing mechanism in which the arm 52 is moved into position to grip the shoe and lift the shoe from its support. As soon as the shoe is lifted from its support the cam wheel 60 140 arrives in position to act on the roll 218 to render the safety mechanism controlled by the arm 32 ineffective throughout the remainder of the cycle of the shoe-removing means.

65 The manner of operation of the mechanism

provided for purposes of this invention has been generally explained in connection with the foregoing description of the construction of the mechanism. Preferably the arm 52 with its shoe-gripping means will start from a position intermediate between the full and dotted line positions illustrated in Fig. 1, and in its cycle of operations it first swings down and grips the shoe as shown in full lines in Fig. 1, then moves reversely through an arc of approximately 180° to the dotted line position in which it automatically releases the shoe, and then returns to starting position. It will be recognized that the mechanism provided is simple in its organization, since the shoe is lifted from its support and is carried to the position in which it is released by a single swinging movement of the arm 52. There is a further advantage also in the provision of means for releasing the shoe in a position in which it is bottom downward, since it will be received in that position by the chute 112 instead of tumbling about with consequent danger on some kinds of work of soiling or otherwise damaging its surface. Moreover, where the shoes are carried away from the machine on a belt conveyor, they will be received by the conveyor from the chute 112 in upright positions and will accordingly be transferred in an orderly manner to the next operating station.

Having described the invention, what I claim as new and desire to secure by Letters Patent of the United States is:—

1. In a machine of the class described, the combination with means for operating on a shoe, of mechanism for removing the shoe from the machine, said mechanism comprising a device constructed to grip the shoe and movable about an axis extending in transverse relation to the height of the shoe to carry the shoe away from the operating vicinity.

2. In a machine of the class described, the combination with means for operating on a shoe, of mechanism for removing the shoe from the machine after the operation of said means thereon, said mechanism comprising a shoe carrier movable about an axis extending in transverse relation to the height of the shoe.

3. In a machine of the class described, the combination with means for operating on a shoe, of mechanism for removing the shoe from the machine, said mechanism comprising a device automatically operative to grip the shoe after the operation of said means thereon and movable about an axis extending lengthwise of the shoe to carry the shoe away from the operating vicinity.

4. In a machine of the class described, the combination with means for operating on a shoe, of mechanism constructed to remove the shoe from the operating vicinity and then automatically to release it, said mechanism comprising a device movable relatively to

- said operating means about an axis extending in transverse relation to the height of the shoe to carry the shoe to the position in which it is released.
5. In a machine of the class described, the combination with means for operating on a shoe, of mechanism constructed to grip the shoe after the operation of said means thereon and to carry it away from the operating vicinity and then automatically to release it, said mechanism comprising a device movable about an axis extending in transverse relation to the height of the shoe to carry the shoe from gripping position to releasing position.
10. 6. In a machine of the class described, the combination with a shoe support arranged to underlie a shoe and means for operating on a shoe on said support, of shoe-discharging mechanism mounted for swinging movement to remove the shoe from said support and carry it to a different location prior to discharging it.
15. 7. In a machine of the class described, the combination with a shoe support arranged to underlie a shoe and means for operating on a shoe on said support, of shoe-discharging mechanism movable about an axis extending in transverse relation to the height of the shoe to remove the shoe from said support.
20. 8. In a machine of the class described, the combination with a shoe support and means for operating on a shoe on said support, of mechanism for removing the shoe from said support and discharging it from the machine, said mechanism comprising a shoe-gripping device mounted for swinging movement to lift the shoe from said support.
25. 9. In a machine of the class described, the combination with a shoe support and means for operating on a shoe on said support, of mechanism constructed to grip the shoe after the operation of said means thereon and to carry it away from the shoe support and then automatically to release it, said mechanism comprising a shoe-gripping device mounted for swinging movement from the position in which it grips the shoe to the position in which it releases it.
30. 10. In a machine of the class described, the combination with a shoe support and means for operating on a shoe on said support, of mechanism for removing the shoe from said support and discharging it from the machine, said mechanism comprising a device constructed to grip the shoe on the shoe support and thereafter to release it and movable about an axis extending in transverse relation to the height of the shoe to carry the shoe from gripping position to releasing position.
35. 11. In a machine of the class described, the combination with a shoe support arranged to underlie a shoe and means for lasting a shoe on said support, of shoe-removing mechanism comprising a shoe carrier mounted for swinging movement and arranged to remove

the shoe from said support by that movement after the operation of the lasting means thereon.

12. In a machine of the class described, the combination with means for operating on a shoe, of shoe-removing mechanism comprising a shoe carrier having shoe-gripping means thereon and mounted for swinging movement toward the shoe into position to grip the shoe and for reverse swinging movement to carry the shoe away from operating position.

13. In a machine of the class described, the combination with a shoe support and means for operating on a shoe on said support, of shoe-removing mechanism comprising a shoe carrier having shoe-gripping means thereon and mounted for swinging movement downwardly into position to grip the shoe and for reverse swinging movement to lift the shoe from said support.

14. In a machine of the class described, the combination with a shoe support and means for operating on a shoe on said support, of shoe-removing mechanism comprising a shoe carrier having shoe-gripping means thereon and mounted for swinging movement about an axis extending lengthwise of the shoe into position to grip the shoe and for reverse swinging movement to remove the shoe from said support.

15. In a machine of the class described, the combination with means for operating on a shoe, of shoe-removing mechanism constructed to carry the shoe away from the operating vicinity and then to release it, said mechanism being movable in such a path as substantially to invert the shoe during its transfer.

16. In a machine of the class described, the combination with means for operating on a shoe, of shoe-removing mechanism constructed to carry the shoe away from operating position and then automatically to release it, said mechanism being mounted for movement about an axis extending lengthwise of the shoe through an arc of approximately 180° in carrying the shoe from operating position to releasing position.

17. In a machine of the class described, the combination with means for operating on a shoe, of shoe-removing mechanism constructed to carry the shoe away from the operating vicinity and then to release it in a position in which it is bottom downward.

18. In a machine of the class described, the combination with means for operating on a shoe, of mechanism constructed to remove the shoe from the operating vicinity and then automatically to release it, said mechanism comprising a shoe-gripping device movable to present the shoe in a position bottom downward when it is released.

19. In a machine of the class described, the combination with means for operating on a

- shoe positioned bottom upward, of mechanism constructed to grip the shoe in that position and carry it to a different position and then automatically to release it, said mechanism comprising a shoe carrier mounted for swinging movement into position to present the shoe bottom downward at the time of its release. 5
20. In a machine of the class described, the combination with a shoe support arranged to position a shoe bottom upward, and means for operating on a shoe on said support, of mechanism constructed to remove the shoe from said support and carry it to a position 10 in which it is bottom downward.
21. In a machine of the class described, the combination with a shoe support arranged to position a shoe bottom upward, and means for operating on a shoe on said support, of mechanism mounted for swinging movement about an axis extending in transverse relation to the height of the shoe to remove the shoe from said support and carry it to a position 15 in which it is bottom downward.
25. 22. In a machine of the class described, the combination with means for operating on a shoe, of shoe-removing mechanism comprising a shoe carrier provided with means for gripping a shoe and for thereafter automatically releasing it, said carrier being mounted 20 for swinging movement only to carry the shoe from gripping position to releasing position.
30. 23. In a machine of the class described, the combination with means for operating on a shoe positioned bottom upward, of shoe-removing mechanism comprising a shoe carrier having means thereon for gripping a shoe and for thereafter releasing it, said carrier being mounted for movement about an axis extending 25 lengthwise of the shoe through an arc of approximately 180° to carry the shoe from gripping position to releasing position.
35. 24. In a machine of the class described, the combination with means for lasting a shoe positioned bottom upward, of shoe-removing mechanism constructed to carry the shoe from that position to a position in which it is bottom downward and then automatically to release it. 40
45. 25. In a machine of the class described, the combination with means for operating on a shoe, of shoe-removing mechanism comprising a shoe carrier movable into position to release the shoe bottom downward, said carrier having thereon shoe-holding means constructed to engage the bottom of the shoe at one end only to permit the shoe to tip out of the carrier when it is released. 50
50. 26. In a machine of the class described, the combination with means for operating on a shoe, of shoe-removing mechanism comprising a shoe carrier movable into position to release the shoe bottom downward, and means for receiving and supporting the shoe by its bottom face when it is thus released. 55
27. In a machine of the class described, the combination with means for operating on a shoe, of shoe-removing mechanism comprising a shoe carrier movable into position to release the shoe bottom downward, said carrier having thereon shoe-holding means constructed to engage the bottom of the shoe at its heel end only to permit the shoe to tip out of the carrier when it is released, and a chute arranged to receive and support the shoe by its bottom face when it leaves the carrier. 60
28. In a machine of the class described, the combination with means for operating on a shoe, of mechanism for removing the shoe from the machine, said mechanism comprising parts relatively movable to grip the shoe in one position and to release it in a different position and mounted for swinging movement to carry the shoe from the position in which it is gripped to the position in which it is released. 65
29. In a machine of the class described, the combination with means for operating on a shoe, said means being movable away from the shoe after operating thereon, of mechanism for thereafter removing the shoe, and automatic means for rendering the shoe-removing mechanism inoperative unless said operating means is away from the shoe. 70
30. In a machine of the class described, the combination with means for operating on a shoe, said means being movable away from the shoe after operating thereon, of mechanism for thereafter removing the shoe, and automatic means for stopping the operation of said shoe-removing mechanism if said operating means is accidentally returned toward the shoe. 75
35. 31. In a machine of the class described, the combination with means for operating on a shoe, said means being movable away from the shoe after operating thereon, of mechanism for thereafter removing the shoe, and a clutch controlled by said operating means for stopping the operation of said shoe-removing mechanism if said operating means is accidentally returned toward the shoe. 80
40. 32. In a machine of the class described, the combination with a shoe support and means for operating on a shoe on said support, said means being movable away from the shoe after operating thereon, of mechanism operative in a predetermined cycle to grip the shoe and remove it from the shoe support and thereafter to release it, and a device arranged to be controlled by said operating means during a portion only of the cycle of operations of the shoe-removing mechanism to render said mechanism inoperative unless said operating means is away from the shoe. 85
45. 33. In a machine of the class described, the combination with a shoe support and means for operating on a shoe on said support, said means being movable away from the shoe 90

after operating thereon, of mechanism operative in a predetermined cycle to grip the shoe and remove it from the shoe support and thereafter to release it, connections controlled by said operating means for stopping the operation of the shoe-removing mechanism if said means is returned toward the shoe, and means for rendering said connections inoperative when said mechanism has completed a portion of its cycle of operations.

34. In a machine of the class described, the combination with means for operating on a shoe, said means being movable away from the shoe after operating thereon, of mechanism for thereafter removing the shoe, automatic means for starting the operation of said shoe-removing mechanism, and additional automatic means controlled by the means for operating on the shoe for preventing the operation of the shoe-removing mechanism unless said operating means is away from the shoe.

35. In a machine of the class described, the combination with means for operating on a shoe, said means being movable away from the shoe after operating thereon, of mechanism for thereafter removing the shoe, two clutches through which said mechanism is operated, means for actuating one of said clutches to start said mechanism, and connections between the other clutch and the means for operating on the shoe to stop the operation of the shoe-removing mechanism if said operating means is accidentally returned toward the shoe.

36. In a machine of the class described, the combination with a shoe support, and lasting mechanism movable away from a shoe on said support after operating thereon, of shoe-removing mechanism movable into a position previously occupied by a portion of the lasting mechanism to grip the shoe, and automatic means for stopping the operation of the shoe-removing mechanism if the lasting mechanism is accidentally returned toward the shoe before the shoe has been removed from the shoe support.

37. In a machine of the class described, the combination with a shoe support, and lasting mechanism movable away from a shoe on said support after operating thereon, of shoe-removing mechanism movable into a position previously occupied by a portion of the lasting mechanism to grip the shoe, automatic means for starting the operation of the shoe-removing mechanism in time relation to the lasting mechanism, and additional means controlled by the lasting mechanism for rendering the shoe-removing mechanism inoperative unless the lasting mechanism occupies a position away from the shoe.

38. In a machine of the class described, the combination with a shoe support, and lasting mechanism movable away from a shoe on said support after operating thereon, of

shoe-removing mechanism operative in a predetermined cycle to grip the shoe and remove it from the shoe support and thereafter to carry it to a different location and release it, and a safety device controlled by said lasting mechanism for stopping the operation of the shoe-removing mechanism if said lasting mechanism is returned accidentally toward the shoe support, said safety device being limited in its action to a portion only of the cycle of operations of the shoe-removing mechanism to permit the lasting mechanism to be returned into position to operate on another shoe while the shoe-removing mechanism is completing its cycle.

In testimony whereof I have signed my name to this specification.

BERNHARDT JORGENSEN.
